(57) **CLAIM**

The ornamental design for a shaving razor handle, as shown and described.

DESCRIPTION

FIG. 1 is a first perspective view of a shaving razor handle showing my new design;

FIG. 2 is a second perspective view of a shaving razor handle of FIG. 1.

FIG. 3 is a third perspective view of a shaving razor handle of FIG. 1.

FIG. 4 is a right side view of the shaving razor handle of FIG. 1.

FIG. 5 is a left side view of the shaving razor handle of FIG. 1.

FIG. 6 is a top view of the shaving razor handle of FIG. 1.

FIG. 7 is a bottom view of the shaving razor handle of FIG. 1.

FIG. 8 is a front view of the shaving razor handle of FIG. 1; and,

FIG. 9 is a rear view of the shaving razor handle of FIG. 1. The broken lines shown in the drawings illustrate portions of the shaving razor handle and form no part of the claimed design.

1 Claim, 7 Drawing Sheets
